(57) **CLAIM**

The ornamental design for a walking cane, as shown and described.

DESCRIPTION

FIG. 1 is a front perspective view of a walking cane showing my new design;

FIG. 2 is a back view thereof;

FIG. 3 is a front view thereof;

FIG. 4 is an enlarged fragmented view of the portion of the cane seen in FIG. 3 inside the dashed reference circle;

FIG. 5 is a left side view thereof;

FIG. 6 is a right side view thereof;

FIG. 7 is a bottom plan view thereof; and,

FIG. 8 is a top plan view thereof.

1 Claim, 4 Drawing Sheets
